UNITED STATES PATENT OFFICE.

ABRAHAM B. LANDIS, OF WAYNESBORO, PENNSYLVANIA.

BOLT CUTTING AND POINTING MACHINE.

948,885.

Specification of Letters Patent.

Patented Feb. 8, 1910.

Application filed October 7, 1905. Serial No. 281,812.

To all whom it may concern:

Be it known that I, ABRAHAM B. LANDIS, a citizen of the United States, residing at Waynesboro, in the county of Franklin and State of Pennsylvania, have invented certain new and useful Improvements in Bolt Cutting and Pointing Machines, of which the following is a specification.

My said invention consists in certain improvements in the construction of machines for cutting threads on bolts, screws, etc., whereby the bolt may also be pointed by the same machine and without removing it, and other detail improvements provided, all as will be hereinafter more fully described and claimed.

Referring to the accompanying drawings which are made a part hereof and on which similar reference characters indicate similar parts, Figure 1 is a side elevation of a bolt cutting machine embodying my said improvements, a portion of one side being broken away showing parts in section in order that the construction may be more clearly illustrated, Fig. 2 a similar view with the bolt pointing mechanism in another position and still more of the side of the machine broken away to show the interior construction, Fig. 3 a cross section looking in the direction indicated by the arrows from the dotted line 3-3 in Fig. 2, Fig. 4 a longitudinal section on the dotted line 4-4 in Fig. 3, Fig. 5 a section on the dotted line 5-5 in Fig. 4, and Figs. 6 to 12, inclusive, detail views of separate parts of the mechanism, illustrating their form and construction more clearly.

In said drawings the portions marked A represent the frame or body of the machine, B the cutter-head, C the bolt holding and feeding carriage and D the pointing device. The frame A is preferably of cast metal, hollow and of suitable size and form to support the several parts of the mechanism and afford suitable bearings and ways for the operative parts of the machine, all as will be hereinafter more fully described.

The cutter-head B is or may be of any approved construction such as shown in my former Letters Patent No. 690,300, 409,208 or in my application No. 281,814 pending concurrently herewith. It is mounted upon a hollow spindle 1, which is mounted in suitable bearings in brackets a and a' on the top of said frame and has a gear 2 on its outer end which meshes with a pinion 3 on the driving shaft 4 of the machine. It carries

the cutter-holders B' containing the cutters forming the cutter-die and adapted to be opened and closed as shown in said patents or the application before referred to.

The means for opening and closing the cutter-die is substantially the same as that shown in my co-pending application No. 281,814, consisting of the lever 14 and the operating mechanism connected therewith which will be hereinafter briefly referred to in describing the operation of the machine.

The bolt holding and feeding carriage C consists of a suitable casting mounted upon longitudinal ways on the body or frame of the machine. It has two transversely sliding blocks C' and C² mounted in suitable ways therein and provided with rectangular recesses in their adjacent faces in which are mounted the holding jaws c and c' provided with serrated notches in their adjacent faces adapted to clamp and hold the bolt. Said jaws may be provided with such notches in each of their four sides, as shown in Fig. 5, and be thus adapted to hold bolts of different sizes, or to be turned to bring different holding faces into operative position when one or another may have been worn to unfit them for use. They are held in position by set-screws c³ mounted in suitable screw-threaded perforations in the blocks C' and C². See Fig. 5. The lower edge of each of the blocks C' and C² is formed concave in cross-section and has screw threads c² cut therein, as best shown in Fig. 6, which is a perspective view of one of said blocks turned upside down.

A transverse perforation is provided through the carriage C beneath the lower edge of said blocks C' and C² and a rod C³ formed with a right-hand screw-thread on one end and a left-hand screw-thread on its opposite end, with a smooth portion in the middle between said screw-threaded portions, is mounted in said perforation, said screw-threads being adapted to engage with the respective blocks C' and C². Said rod C³ is held in position by a short split sleeve C⁴ mounted on said rod between the two collars c⁵ and c⁶ located one at the inner end of each of the screw-threaded portions. Said sleeve is provided with a V-shaped groove c⁷ with which a set-screw c⁸ mounted in the front of the block C (see Fig. 4) is adapted to engage and lock said collar and thus lock said screw-threaded rod C³ in position. A hand-wheel C⁹ is mounted on the outer end of said rod C³ by which it may be turned and the blocks

C' and C² thus operated toward or from each other to clamp or release a bolt placed between the jaws c and c', as will be readily understood. Said carriage C is provided 5 near its rear end with a transverse shaft C⁶ mounted in suitable bearings and having a gear-wheel or pinion c⁶ mounted thereon, which is adapted to engage with a longitudinal rack-bar C' secured rigidly to the 10 frame A. A hand-wheel c⁷ is mounted on the outer end of said shaft by which it may be turned and the carriage C thus moved back and forth on the ways upon which it is mounted to feed the bolt to the cutting or 15 turning head and withdraw it therefrom, as desired.

The turning-head D consists of a hollow cylindrical part or socket having a cutter d mounted therein adapted to receive the end 20 of the bolt and turn it to a conical or rounded form. Said turning head is mounted upon a horizontal rod D' which extends through a central perforation in the cutter-head B and in the spindle 1 upon which said 25 cutter-head is mounted, suitable bearings being formed for said rod in said parts through which it is adapted to slide back and forth. A collar d' is mounted rigidly upon the rear end of said rod and a vertical lever D² is 30 pivotally connected at its upper end to said collar. Said lever D² is pivoted at its lower end on a pivot d² to the outer end of an arm D³, which is connected to the frame A by means of a pivot d³ extending through ears 35 a⁴ on the side of said frame, as shown. The lower end D⁴ of said lever D² is turned to a position at right angles with the main part and is provided with a set-screw d⁴, which is 40 adapted to strike against the under side of the arm D³ and limit the movement of said lever and thus adjust the length of the throw of its upper end.

A spring D⁵ is mounted on the top of arm D³ and adapted to bear against the front 45 edge of lever D and normally tend to throw said lever from the position shown in Fig. 2 to that shown in Fig. 1. Said lever D² is formed at a point near its upper end with an opening in which a sleeve D⁶ is mounted 50 on pivots d⁶, which permit said sleeve to remain in a horizontal position regardless of the movements or the angles of said lever. A rod D⁷ is mounted in said sleeve at this end and at its opposite end is rigidly secured 55 in a downwardly projecting arm C⁸ on the carriage C being secured by a clamping screw c⁸ which extends through flanges on each side of a split in the side of the wall of the perforation through which said rod 60 passes. Said rod is thus made to move with said carriage. It is provided with a latch d⁷ mounted in a slot therein on a pivot d⁸, the engaging point of said latch being adapted to engage with the rear end of the sleeve 65 D⁶ where the lever and rod are brought to

the position shown in Fig. 2. Another latch A⁴ is mounted on a projecting part a⁸ of the frame A by means of a pivot a⁵ being held in a substantially horizontal position by means of a spring a⁶ between said projecting part 70 and the heel h of said latch. The catch a⁷ of said latch is adapted to engage with a transversely extending latch-pin d⁹ on the side of lever D². Said latch A⁴ has an upwardly extending arm a⁹ with a tapered or 75 cam-shaped top adapted to engage with a tapered shoulder s in the rod D⁷. A set-screw a¹⁰ is mounted in an upper part of the projection a⁸ and adapted to contact with the upper projecting end d¹⁰ of the pivoted 80 latch d⁷.

The operation of the machine is as follows: When the parts are in the position shown in Fig. 1 the cutter-die is closed and the parts are in position to cut the threads 85 upon the bolt, which is done in the usual manner. The carriage C is fed forward and carries with it the rod D⁷ until said carriage has reached the position where the arm 10 thereon will strike the nut 11 on the screw 90 rod 12 and release the latch 13 from engagement with the lever 14, which permits the spring 15 to pull back the lower end of said lever 14 by means of its pivoted connection with the rod 16 and allow the cutter-die to 95 open. At the same time the rod D⁷ has been carried to the point where the latch d⁷ will have passed through the collar D⁶ in the lever D² and its point will have engaged with the outer end of said collar, locking said lever D² to said rod D⁷ and through it to the carriage C. Thus as the carriage is moved back said lever D² and the rod D⁷ connected therewith, carrying the point cutting-die, is drawn forward until it reaches the position 10 shown in Fig. 2 with said point cutting-die extending through the cutter-head, the die of which is then open. At the same time the latch A⁴ will engage with the latch-pin d⁹ of lever D² and lock said lever and the point 11 cutting-die securely in this position. The carriage is then run back until the end of the bolt comes within the point cutting-die D and is pointed by the rotation of said die, which operation does not disturb the positions of the several parts. When the operation of pointing is completed the carriage is again run back to a point where the arm 10 thereon will strike the nut 17 on the rod 16 and through it draw the lever 14 back to a 120 position to operate the cam-ring B² to close the cutter-die, when the latch 13 will fall into engagement over the latch pin on said lever 14 and lock said parts in position to cut the thread upon the next bolt. Just before 125 the carriage C has reached the position to close the thread cutting-die the tapered shoulder s on the rod D⁷ comes in contact with the tapered top of the arm a⁹ of the latch A⁴ and forces said latch out of en-130

gagement with the latch pin d^9 of the lever D^2 . The upper projecting end d^{10} of the latch d^7 also passes under the lower end of set-screw a^{10} and is forced down so as to raise its opposite end d^7 out of engagement with the front end of collar D^6 . The spring D^5 then operates to throw said lever D^2 from the position shown in Fig. 2 to that shown in Fig. 1, this movement being limited by the set-screw d^4 . Said point cutting-die is thus thrown out of the way of the operation of the thread cutting mechanism.

The operation of cutting the thread and pointing the bolt is thus alternately and continuously performed by the same machine and without removing the bolt therefrom until both operations have been completed, thus securing an improved product by an economical method.

Having thus fully described my said invention; what I claim as new and desire to secure by Letters Patent, is:—

1. In a bolt cutting and pointing machine, the combination of the cutter-head formed with a central perforation and mounted upon a hollow spindle, the work holding and feeding carriage, the pointing die or cutter mounted to reciprocate within the cutter-head and mechanisms connected with and operated by said work-holding and feeding carriage for extending said pointing die through the cutter-die of said cutter-head when the same is open, in position for pointing the bolt, substantially as set forth.

2. In a bolt cutting and pointing machine, the combination of the cutter-head carrying the thread cutting die, mechanism for opening and closing said die, a pointing die mounted to reciprocate in a central perforation in said cutter-head and extended through the thread cutting die, when it is open, in position to point the bolt, means connected with the work-holding and feeding carriage for reciprocating said die, means for holding said pointing die in operative position, means for withdrawing said pointing die to within the cutter-head when the operation is completed, and the work holding and feeding carriage, substantially as set forth.

3. In a bolt cutting and pointing machine, the combination of the cutter-head carrying the thread die, means for opening and closing said die, a pointing die mounted to reciprocate within a central perforation in said cutter-head, the work holding and feeding carriage, a connection extending from said carriage to a means for reciprocating said pointing die, said means, means connected with said carriage for operating the opening and closing mechanism of the thread cutting die, and means for locking the dies alternately in their respective operative positions and releasing them and returning them out of the way of the opera-

tion of the next to be used, substantially as set forth.

4. In a bolt cutting and pointing machine, the combination of the carriage, the cutter-head carrying the thread cutting die, mechanism for opening and closing said thread cutting die, a pointing die mounted to reciprocate within a central perforation in said cutter-head, means for holding said pointing die forward to extend through the thread cutting die in position to point the bolt, and means controlled by the carriage for withdrawing said pointing die and closing the thread cutting die after the pointing operation is completed, substantially as set forth.

5. In a bolt cutting and pointing machine, the combination of the cutter-head carrying the thread cutting die, mechanism for opening and closing said thread cutting die, the bolt holding and feeding carriage, a connection from said carriage to the mechanism for opening and closing said thread cutting die, whereby as said carriage reaches one position said die is closed and locked and as it reaches another position said die will be opened, the pointing die mounted within a perforation in said cutter-head and connected with means for projecting it forward through the thread cutting die, when open, and locking it in position to point the bolt, said means and a connection between said means and said carriage whereby said pointing die is extended forward into operative position as the thread cutting die is opened and returned out of the way of said thread cutting die when its operation is finished, substantially as set forth.

6. In a bolt cutting and pointing machine, the combination of the carriage, a cutter-head carrying the thread cutting die, a pointing die mounted in a central perforation in said cutter-head, and means controlled by the carriage for reciprocating said pointing die into and out of operative position between the operations of said thread cutting die, substantially as set forth.

7. In a bolt cutting and pointing machine, the combination of the cutter-head carrying the thread cutting die, the pointing die mounted in a central perforation in said cutter-head, means for opening and closing the thread cutting die, a pivoted lever connected with the rear end of the stem of the pointing die and containing an aperture, the work carrying carriage, a rod rigidly connected with said carriage and containing an adjustable latch adapted to extend through the aperture in said lever and engage with its outer face, whereby when the carriage is pulled back said lever will be drawn forward and said pointing die projected through the thread cutting die, a latch pivoted to the frame adapted to engage with a catch on said lever and lock it in position, means controlled by the carriage for releas-

ing said catch when the pointing operation is completed, and a spring for throwing said lever and pointing die back out of the way of said thread cutting die, substantially as set forth.

8. In a bolt cutting and pointing machine, the combination of the cutter-head carrying the thread cutting die, means for opening and closing said thread cutting die, comprising an operating lever, a latch pivoted to the frame adapted to engage with a latch-pin on said lever and hold it in position to lock said die closed, the work holding and feeding carriage, a connection between said work holding and feeding carriage and said lever, whereby said thread cutting die is opened and closed by the movements of said carriage, the pointing die mounted within a central perforation in said cutter-head, the stem whereof extends through the hollow spindle of said cutter-head and is pivotally connected with a vertical lever pivoted at its lower end to a projection from the side of the frame and provided at an intermediate point with means for engaging and disengaging with a rod connected rigidly with said carriage, said rod being adapted to engage with said lever at the point where the carriage is in the position when the thread cutting operation is finished, whereby, as said carriage is backed to carry the bolt out of the thread cutting die, the pointing die is brought forward to project through said

thread cutting die after it is automatically opened by the mechanism connected with said carriage, means for locking said die in position, and means connected with said carriage for releasing said locking mechanism and permitting said pointing die to return out of the way of the thread cutting die, substantially as set forth.

9. In a bolt cutting machine the combination with the various operating mechanisms of the carriage for holding and feeding the work comprising a block having a central recess with two sliding blocks mounted in transverse ways carrying the holding jaws and a screw-rod mounted in a transverse perforation in said carriage and formed with a right-hand thread upon one end and a left-hand thread upon the other adapted to engage with screw-threads on the under face of said sliding blocks, and means for holding said screw-rod in position comprising a sleeve mounted upon a central smooth portion thereof between two collars and secured to the carriage by a transverse set screw, substantially as set forth.

In witness whereof, I have hereunto set my hand and seal at Waynesboro, Pennsylvania this 8th day of September, A. D. nineteen hundred and five.

ABRAHAM B. LANDIS. [L. S.]
